DESIGN FOR AN AIRPLANE

Theodore P. Hall, San Diego, Calif., assignor to
Consolidated Vultee Aircraft Corporation, San
Diego, Calif., a corporation of Delaware

Application November 29, 1944, Serial No. 116,609

Term of patent 14 years

(Cl. D71—1)

To all whom it may concern:

Be it known that I, Theodore P. Hall, a citizen of the United States, residing at San Diego, in the county of San Diego and the State of California, have invented a new, original, and ornamental Design for an Airplane, of which the following is a specification, reference being had to the accompanying drawings, forming a part thereof:

In the drawings:

Figure 1 is a perspective view of an airplane, showing my new design;

Figure 2 is a front elevational view;

Figure 3 is a top plan view;

Figure 4 is an enlarged elevational view of the starboard side of the airplane; and

Figure 5 is an enlarged elevational view of the port side.

I claim:

The ornamental design for an airplane, substantially as shown.

THEODORE P. HALL.
